(57) **CLAIM**

The ornamental design for a slip resistant sole, as shown and described.

DESCRIPTION

FIG. 1 is a perspective view of a slip resistant sole showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view; and,

FIG. 7 is a perspective view of FIG. 1 with a portion enlarged to show detail.
